UNITED STATES PATENT OFFICE.

HENRY HANDY, OF PHILADELPHIA, PENNSYLVANIA.

DESIGN FOR A CAKE OR BREAD PAN.

SPECIFICATION forming part of Design No. 35,040, dated September 3, 1901.

Application filed August 2, 1901. Serial No. 70,676. Term of patent 7 years.

To all whom it may concern:

Be it known that I, HENRY HANDY, a citizen of the United States, residing at the city of Philadelphia, in the county of Philadelphia and State of Pennsylvania, have invented and produced a new and original Design for Cake or Bread Pans, of which the following is a specification, reference being had to the accompanying drawings, forming part hereof, in which—

one, *a*, is convoluted or scalloped and the inner one, *b*, is straight or geometrical. As 25 viewed in section, from a central rectangular opening *d'* in the flat base *d* of the pan project upward the walls *b'* of the inner rectangle *b*, while from the outer perimeter of the flat base *d* the convoluted walls *a'* of the outer rectangle *a* project upward in divergent planes; but the walls *a'* do not extend upward as far as the walls *b'*.

Having thus described my invention, what I claim as new, and desire to secure by Letters 35 Patent, is—

The design for a cake or bread pan, substantially as herein shown and described.

In testimony whereof I have hereunto set my signature in the presence of two subscribing witnesses.

HENRY HANDY.

Witnesses:

J. WALTER DOUGLASS,
THOMAS M. SMITH.
